UNITED STATES PATENT OFFICE.

STEUBEN T. BACON, OF BOSTON, MASSACHUSETTS.

IMPROVEMENT IN LIGHT-INTENSIFYING ATTACHMENTS FOR GAS-BURNERS.

Specification forming part of Letters Patent No. 127,829, dated June 11, 1872.

To whom it may concern:

Be it known that I, STEUBEN T. BACON, of Boston, Suffolk county, Massachusetts, have invented certain new and useful Improvements in Light-Intensifying Attachments for Gas and other Burners, of which the following is a specification:

This invention has for its object the concentration of the light from the flame of a gas or other burner, whereby an increased and concentrated light may be thrown upon any surface where such light is required, either for artists' work or for other purposes. To effect this result I make use of a plano-convex lens of glass, which is hinged to a bracket, which, in turn, is hinged to an arm projecting from and adjustable upon the gas or other fixture for producing an illuminating flame, there being at each of the hinged joints a set-screw, by which the lens or its bracket, when adjusted to any desired position, may be firmly fixed and held in that position.

I have represented the manner in which my invention is or may be carried into effect in the accompanying drawing which represents a perspective view of the device attached to the standard of a gas-burner.

A is a plano-convex lens of glass, pivoted or hinged in a metallic bracket, B, being hung on the shanks of set-screw *a*, whose inner ends screw into sockets formed for them in the lens or in a suitable frame encircling the same. The lens swings on these set-screws, and, after being placed at any desired inclination, may be there held by tightening up the screws. The bracket B has a shank, C, whose lower end fits between the forked end of a metallic arm, D. A set-screw, *b*, passes loosely through one prong of the fork and the intermediate shank, and screws into and through the opposite prong of the fork, so that, after setting the bracket at any angle, it may be held in its position by tightening up the set-screw. The arm D at its other end fits around the standard E of the gas fixture, and is capable of sliding up and down thereon; and it carries a set-screw, *c*, by which it may be held firmly at any desired elevation on the standard. The arm

also turns on the standard, so that the attachment may be adjusted to any point around the burner. The arm may be of less length than represented, if desired.

I am aware that it has been proposed to use with a gas-burner a light-concentrating attachment, the lens of which is formed of water contained in a hemispherical cup. But this device is inconvenient on several accounts. The surface of the water becomes soon covered with impurities, and the water clouded with dust and other foreign matter, so that the cup must be frequently emptied and refilled, and it is not practicable to use this device with any other than a horizontal burner, and in other than a horizontal position, otherwise the water would be spilled. And, again, the device is sensitive to very slight vibrations, which produce corresponding movements of the surface of the water, and thus interfere with the steadiness of the concentrated light. In the improved device which I have above described these objections are obviated. The lens can be used with a horizontal or vertical or inclined burner. It can be set at any angle to concentrate the light upon a surface either directly below or to one side of the burner.

Having described my invention and the manner in which the same is or may be carried into effect, I would say that I do not limit my claim to the precise number of joints herein described, nor to the precise means of effecting the adjustment of the different parts, for it is manifest that these may be varied without departure from the invention, all that is necessary in this regard being that the attachment should be capable of adjustment so as to concentrate the light upon any side of the burner, and either directly below it or obliquely from or to one side of it, whether the burner be vertical, horizontal, or inclined.

I would further observe that I do not claim as my invention the glass lens of plano-convex form, as that has been known before my said invention; but—

What I claim, and desire to secure by Letters Patent, is—

A light-intensifying or concentrating attachment for gas and other burners, consist-

ing of a glass lens, in combination with a frame or support, constructed substantially as herein described, so that it may be attached to and adjustable upon the gas or other fixture, and so that the lens may be adjusted and set in any desired position with respect to the flame, as and for the purposes set forth.

In testimony whereof I have signed my name to this specification before two subscribing witnesses.

STEUBEN T. BACON.
